TO TEXAS GULF SULFUR COMPANY, OF NEW YORK, N. Y., A CORPORATION OF
TEXAS

MINING OF SULPHUR

Application filed September 22, 1926. Serial No. 137,098.

This invention relates to improvements in the mining of sulphur, and includes an improved method for the mining of sulphur by underground fusion, as well as an improved system or apparatus therefor.

In the mining of sulphur by underground fusion, in accordance with the so-called Frasch process, a hole or well is drilled through the overlying strata to the bottom of 10 the sulphur formation, which hole is usually cased with an eight-inch or ten-inch pipe, and then, through a system of concentric pipes appropriately arranged within this casing, superheated water is pumped down to the 15 foot of the hole or well where it is discharged into the sulphur formation and melts the sulphur. The melted and liquid sulphur enters one of the concentric pipes, usually through a strainer, and is raised to the surface of the 20 ground, generally by means of an air lift. The well continues to operate and produce sulphur until the sulphur-bearing formation is locally exhausted, or until the piping equipment is broken by subsidence of the ground 25 due to the extraction of the sulphur content.

The sulphur formation is usually found in the form of so-called domes, at depths varying from around 500 to 1500 feet below the surface of the ground. These sulphur domes are 30 usually overlaid by a porous cap rock formation of limestone which in turn is overlaid by gumbo, quicksand and clay. Beneath the sulphur formation is usually found a layer of gypsum or anhydrite, and layers or domes 35 of salt.

The sulphur formation itself usually contains the sulphur distributed in a porous rock formation which also contains a large amount of water forming what may be considered an 40 underground lake of brine or salt water containing, for example, about 4800 grains per gallon of solids in solution, mainly sodium chloride, and in addition hydrogen sulfide and other soluble sulfides.

45 In the so-called Frasch system of mining sulphur by underground fusion, hot water is the vehicle commonly used for conveying and transmitting heat to the sulphur. Inasmuch as sulphur melts at a temperature around 50 240° F. which is above the boiling point of

water at atmospheric pressure, the heating water is highly superheated and is pumped into the mine under a high pressure. The temperature to which the water can be superheated is however limited by the danger of 55 overheating the sulphur in which case it becomes viscous. Accordingly, the water is heated to a temperature which avoids overheating of the sulphur but which is sufficiently above the melting point of the sulphur 60 to bring about effective melting thereof as the highly heated water comes in contact with the underground sulphur. The water may thus be heated under pressure to about 320° F. and pumped into the sulphur deposit, this 65 water replacing the sulphur removed by the well together with water already contained in the deposit, which may be withdrawn by means of bleed-wells, situated at suitable points in the deposit. The bleed-wells are 70 usually located so as to withdraw the cold brine or salt water from the lower part of the sulphur formation.

The sulphur dome may underlie a considerable surface area of ground. The dome 75 may, for example, be as much as a mile in diameter; and the underground lake forming a part of the deposit or adjacent thereto may contain billions of gallons of underground water or brine.

In the mining of such a sulphur deposit, one or several wells are usually drilled and operated at one part of the deposit until the sulphur bearing formation is exhausted locally and then other wells are drilled at 80 another part of the deposit, and the deposit is progressively worked in this way until exhausted. The operation of a sulphur mine in this way is an operation of large magnitude. The amount of highly heated water 85 which it is necessary to pump into the deposit in a single day may amount to several million gallons in commercial operations.

The pumping of a large amount of superheated water into the deposit results in the 90 gradual accumulation of a progressively increased amount of hot water in the deposit. The specific gravity of the original deposit water is for example about 1.08, and the temperature for example about 108° F.; while 95 100

the specific gravity of the clean hot water pumped into the mine is in the neighborhood of 0.91. Owing to this difference in specific gravity, the hot water rises or tends to rise to the top of the dome, displacing the cold deposit water downward, and, while there is some diffusion and mixing, in a general way the water at the top of the dome becomes cleaner and hotter with only a small amount of solids in solution, while the water in the lower part of the deposit contains its original content of dissolved solids until displaced by the cleaner water from above.

The continued supply of a large amount of highly heated water to the mine forms one of the major expenses of the operation, this water being commonly obtained from a source several miles distant from the mine at a temperature around, for example, 68° F., and being heated to a temperature around 324° F. before it is pumped into the mine. Of the total heat supplied to the water, only a small part is available for melting the sulphur. Thus, in heating water from 68° F. to 324° F., 256 B. t. u's are supplied by the combustion of fuel to each pound of water which is pumped into the deposit. Since sulphur melts at around 240° F. the only effective heat supplied to the water is that between the maximum temperature of the water and the melting point of sulphur, for example, around 85 B. t. u's of the total of 256 B. t. u's supplied to the water.

The present invention provides an improved method and system of mining sulphur whereby important economy of operation is obtained, and whereby a greatly increased fuel efficiency, and decreased fuel consumption can be effected.

The present invention is of particular advantage in the mining of sulphur from deposits which have been operated for considerable time until there has accumulated a large amount of hot water in the upper portion of the dome or formation from which the sulphur has been exhausted. After long periods of operation, the temperature of this hot water, accumulating in the upper portion of the dome, will be considerably above the melting point of sulphur, which is about 240° F. and the temperature of this water may be as high as 300° F. or even higher. This hot water is contained under considerable pressure, which pressure is usually in excess of the hydrostatic pressure.

The present invention is a modification of the invention of my Patent No. 1,615,051 and includes the invention of said application, together with modifications thereof which result in a modified and improved method of mining of the sulphur.

According to the present invention, I make further use of the accumulated hot water in the dome and take advantage of the heat which it contains by withdrawing hot water

from the top or upper part of the dome or deposit where it accumulates in the exhausted area and in the porous cap rock, maintaining this water under pressure to prevent vaporization and cooling, and again forcing it down into the deposit through a well or wells where active mining operations are going on; and, in conjunction with such withdrawal and reutilization of the accumulated hot water, I operate other wells with fresh hot water so that the accumulated supply of hot water in the deposit is replenished from the hot water so introduced at the same time that the accumulated supply is being utilized for further mining operations.

The continued and prolonged withdrawal and reutilization of accumulated hot water in the manner described in my companion application, will, unless additional heat is supplied, gradually lower or tend to lower, the temperature of the hot underground lake in the deposit, and particularly of the hottest part of this accumulated supply which tends to accumulate in the upper levels of the deposit. By operating wells in which fresh hot water is supplied in conjunction with other wells in which hot recirculated mine water is used, the loss in heat due to the recirculation is more or less compensated for by the additional heat supplied by the fresh hot water, which as hereinbefore pointed out, is heated to a temperature considerably in excess of the melting point of the sulphur. This fresh water, because of its high temperature, will rise or tend to rise to the top of the deposit and to the upper levels of the accumulated underground supply of hot water, thereby replenishing the supply from which the recirculated hot water is withdrawn for further use in mining operations.

The wells which are operated with fresh hot water can be operated in accordance with the present day mining operations, according to the so-called Frasch method, hereinbefore described and will result in an increase in the amount of hot superheated water under pressure contained in the deposit. The wells operating upon recirculated hot water from the deposit can be operated in accordance with the process more fully described in my Patent No. 1,615,051. The combined operations of wells in accordance with both procedures, and with withdrawal of cool or cold water through so-called bleed-wells from a lower level of the deposit, tends to maintain constant or to slowly and gradually increase the supply of underground hot water and tends to maintain or to slightly increase or decrease the temperature of such body, while tending further to insure a supply of hot water at a sufficiently high temperature in the upper part of the deposit from which the water is withdrawn and recirculated to a remote well zone for further use in the mining operation.

The hot recirculated water which is sufficiently above the melting point of sulphur to enable it to be used without further heating, is maintained under pressure and with little if any loss in temperature while it is being withdrawn and reintroduced through the active sulphur mining well or wells. The hot water so introduced in the localized well zone will tend to rise again, after serving its purpose of melting sulphur, to unite with the large body of hot water in the top of the deposit. The gradual withdrawal of hot water in this way, with return of the hot water withdrawn to the deposit, will result in a tendency to reduce the temperature of the hot water in the deposit, but after a large underground lake of hot water has been accumulated by prolonged mining operation with fresh hot water, this tendency will not be felt until after operations have continued for a considerable time; and, by the introduction of additional fresh hot water at other operating wells, this tendency may be overcome either completely or sufficiently to insure continuation of the recirculation without reduction of temperature below that which will be sufficient in the withdrawn and recirculated water.

Inasmuch as the continued introduction of fresh hot water increases the amount of water in the deposit, a corresponding amount of cool or cold water can advantageously be withdrawn from a lower level of the deposit through one or more bleed-wells, thus maintaining substantially constant the amount of underground water and tending to increase the accumulated supply of hot water. This increase in supply will be much less than would be the case if fresh hot water were used in all of the active wells, but it is nevertheless sufficient to avoid undue cooling of the accumulated water supply by admixture of cold water or by the cooling of the recirculated water through the recirculating lines or through the operating wells in which the recirculated water is employed.

In carrying out the recirculation of the accumulated hot water according to the process of the invention, this accumulated hot underground water which is at a high temperature and pressure, e. g. considerably in excess of 240° F. and up to around 300° F. or more, and at a pressure greater than atmospheric, is withdrawn and kept under pressure while it is being withdrawn, by means of a pump, a steam injector or other suitable means, and this water so withdrawn under pressure and with its temperature maintained by the pressure and by preventing vaporization, is again introduced into the deposit for further use in the mining operation.

One advantageous method of maintaining this water under pressure, and of preventing it from being cooled below 240° F. through reduction of its pressure, is to introduce a cen-

trifugal pump into the line through which the water is withdrawn, and at a sufficiently low level to receive the water while still under sufficient pressure to prevent its partial vaporization.

The hot water thus withdrawn may, if desired, be purified, but ordinarily it can be used again without purification. So also, the water withdrawn may be subjected to further heating, as by injection of steam, but if the water is at a sufficiently high temperature it can be used again without further heating.

The invention will be further described in connection with the accompanying drawing, which illustrates in a conventional and graphic manner a section of a mine and of apparatus embodying the invention and adapted for the practice of the process of the invention.

The showing is largely conventional, and various parts are magnified, and the horizontal dimensions of the pipe and of various parts are magnified for convenience of illustration.

In such a mine as represented in the accompanying drawing, the sulphur deposit is usually overlaid by a cap rock formation of limestone, above which is gumbo, quicksand and clay. Below the sulphur deposit there are usually bodies of gypsum and salt. In the drawing, there is represented a region marked "Hot water zone" from which it is assumed the sulphur has been melted, and which is assumed to be full of hot water accumulated from the mining operation. The hot water will also extend upwardly into the porous caprock. It will be apparent that as the sulphur is melted and withdrawn, the space originally occupied by the sulphur must be filled either by the subsidence of the earth above or by the hot water pumped into the mine. It will also be understood, as above explained, that the hot water which is pumped into the mine where the active mining operation is going on, is lighter than the cold salt water originally contained in the mine, so that the fresh hot water tends to rise and to accumulate in the upper levels of the dome.

In the drawing, one of a series of active sulphur wells is indicated at 1, this well being made up as usual of a series of concentric pipes within a casing tube. For convenience of illustration, the entire series of pipes is omitted and only two concentric pipes are shown, the inner pipe 3 being intended to illustrate graphically the pipe through which the molten sulphur is pumped from the mine and which extends to the bottom of the deposit, and the outer casing 2 illustrating the outer pipe within which the hot water is pumped down into the mine.

Another active or a series of active sulphur wells is indicated at 20, this well being similar in construction to the well 1 except for the supply of fresh hot water instead of re-

circulated hot water. The fresh hot water is supplied through the pipe 21 from a power plant suitably located and the molten sulphur is drawn off through the pipe 22 in the usual manner.

- 5 One or more bleed-wells 5 may be located at a distance from the active sulphur mines leading from a lower level of the deposit from which the colder water may be withdrawn in regulated amount at suitable locations.
- 10 One or more wells 6 may be located so as to withdraw water from the top of the dome. Such wells extend down into the porous cap-rock and at their upper ends are enlarged so as to accommodate a suitable pump, shown as a centrifugal pump 8 driven by a motor 9 and having an extension 10 extending down into the hot water zone and which may terminate in a perforated end 11 through which the hot water is admitted into the pipe 10 and thence into the centrifugal pump 8. The well pump 8 may be of any suitable construction for keeping the water under pressure so that no expansion or freeing of steam can take place near or at the surface of the ground. A heavy duty centrifugal pump such as a Layne multi-stage centrifugal pump can be used. This pump should be located at a sufficient distance below the surface of the ground to receive the water before its pressure has been reduced sufficiently to permit vaporization and cooling thereby. The pump may be located for example from 60 to 100 feet below the surface of the ground, or it may be located at even a lower level if desired or necessary.

40 The water pumped from the ground passes through the pipe 13 to the well 1 where it is again forced down into the ground. A pump 17 is provided which may supplement the centrifugal pump 8, but with a suitable centrifugal pump, the pump 17 may be omitted, or may be used only for supplementing the centrifugal pump as occasion may arise for doing so.

45 By withdrawing the hot water from the mine in this way and maintaining it under pressure and at its original temperature, or with only a minimum drop in temperature, the water can be used over again in a different location of the mine for melting further amounts of sulphur. This reutilization of the hot mine water results in large economies as compared with ordinary mining operations where all of the hot water utilized in the mining operation is fresh water which requires heating, e. g. from around 68° F. to around 324° F. By reutilizing the accumulated supply of hot water in accordance with 50 the present invention, the amount of fresh hot water employed can be greatly reduced and the consumption of heat required for heating fresh water for the entire mining operation can be greatly reduced.

55 At the beginning of the mining operations

of the dome, the sulphur wells are usually located near the top of the dome near the location of the well 6 and such wells are operated until the sulphur is exhausted at that location or until subsidence of the ground causes breaking of the piping equipment. As the ground surrounding the first wells becomes exhausted, additional wells are drilled at a distance from the first wells. These wells may be at a location such as 70 illustrated by the well 1 in the drawing and the well 6 may be an exhausted well which is used merely for the purpose of withdrawing the hot water from the upper part of the deposit. The upper part of the deposit forms 75 a heat reservoir where the hottest water tends to accumulate in a portion of the deposit from which the sulphur has been exhausted and in the porous caprock where it serves no useful purpose in melting sulphur and where 80 it causes great heat loss and low heat efficiency.

85 Such operations represent the usual operations. Instead of continuing these operations in the usual way, they are continued, 90 according to the present invention, on a reduced scale as compared to the entire mining operation, and such reduced operation is combined with the recirculation of water from the deposit in such a way that it is employed instead of fresh hot water for part 95 of the mining operation.

If the hot water withdrawn from the deposit had its pressure reduced to atmospheric, the reduction in pressure would cause 100 reduction in temperature by vaporization and the water escaping at the surface of the ground would have a temperature not exceeding 212° F. which would be too low for further use without reheating in the melting 105 of sulphur.

According to the present invention, such reduction in temperature due to vaporization is avoided by maintaining the hot water under a sufficient pressure to prevent cooling 110 by vaporization so that it can be maintained at substantially its original temperature and reintroduced into an operating well or wells while still under pressure and at approximately its original temperature. If, for example, the temperature of the accumulated body of hot water in the deposit is in the neighborhood of 275 to 300° F., this water is withdrawn under sufficient pressure to prevent vaporization and cooling and is kept 115 under pressure and forced again down into the deposit at the operating well or wells at a temperature approximately the same as that of withdrawal from the underground body of hot water or with only a small temperature drop due to heat losses other than by vaporization during the recirculation.

120 Along with the operation of such wells with recirculated hot water from the deposit, other wells are operated with fresh super- 125

heated water introduced in accordance with present day practice, and these operations with fresh superheated hot water supplement those with recirculated hot water in the manner hereinbefore described to overcome un-
5 due cooling of the recirculated water and to replenish the supply of accumulated hot water at the top of the deposit from which the recirculated water is withdrawn.

With the combined operations of the pres-
10 ent invention there will be underground cir-
culation of both the fresh hot water and of
the recirculated hot water. The hot water,
whether fresh or recirculated, will be intro-
15 duced at wells where sulphur is being melted
and where part of the heat of the hot water
is utilized for such melting. The water after
such use tends to flow to the upper part of
the deposit to admix with the accumulated
20 supply there. The recirculated water will
be somewhat lower in temperature than when
withdrawn, while the fresh hot water from
the wells where it is used will ordinarily be
at a somewhat higher temperature than the
25 water withdrawn. The composite result will
be to maintain the temperature of the water
withdrawn so that it does not vary greatly
and does not fall below an active melting
temperature even after long continued use of
30 accumulated hot water by recirculating and
reutilizing it in the manner described.

The present invention includes as an appa-
ratus or system, an arrangement of wells, one
or more of which is connected to and operated
35 with a supply of fresh hot water, one or
more of which is connected with the hot
accumulated body of water in the dome and
one or more of which are used as the active
operating wells, with outside connections
40 such that the water can be withdrawn and
directly reintroduced, without substantial
loss of temperature, and maintained con-
tinuously under pressure.

Where the mining operation is carried out
45 with a hot brine of high specific gravity,
which tends to settle to the bottom of the sul-
phur deposit, this accumulated, heavy brine
can, after it has reached a sufficient volume
and temperature, be withdrawn and reintrodu-
50 ced in a similar manner to that above de-
scribed in connection with the use of hot
water. The operation will be somewhat re-
versed, however, in that the heavy brine will
be introduced at a higher level than that from
55 which it is withdrawn and the accumulated
body of hot brine will be in the lower parts
of the sulphur mine or deposit rather than
in the upper portion thereof.

I claim:

60 1. The improvement in the mining of sul-
phur by underground fusion from partially
exhausted sulphur deposits, which comprises
withdrawing from the upper part of a de-
posit hot water at a temperature higher than
65 the melting point of sulphur, maintaining the

temperature of the water above the melting
point of sulphur, reintroducing the with-
drawn hot water into the deposit at a local-
ized well zone remote from the point of with-
drawal and coincidentally therewith introduc-
70 ing fresh hot water into and removing sul-
phur from the deposit at another localized
well zone.

2. The improvement in the mining of sul-
phur by underground fusion from partially
75 exhausted sulphur deposits, which comprises
withdrawing from the deposit hot brine at a
temperature considerably above the melting
point of sulphur, maintaining the withdrawn
brine under pressure to prevent vaporization
80 and cooling below the melting point of sul-
phur, reintroducing the withdrawn hot brine
into the deposit at a well zone remote from
the point of withdrawal and coincidentally
therewith introducing fresh hot brine into
85 and removing sulphur from the deposit at an-
other localized well zone.

3. In the mining of sulphur by under-
ground fusion from partially exhausted sul-
phur deposits, one or more wells arranged to
90 permit the withdrawal of hot water at a tem-
perature above the melting point of sulphur
from near the top of the deposit, one or more
wells arranged for conducting superheated
water into the sulphur containing formation,
95 means for pumping hot water from the said
withdrawing wells and maintaining it under
pressure from the top of the deposit to the
surface of the ground, means for reintroduc-
ing, still under pressure, the withdrawn hot
100 water into the sulphur mining well or wells as
the heating medium therefor and one or more
wells provided with a supply of fresh super-
heated water arranged to introduce the same
into the deposit and to remove molten sulphur
105 therefrom.

4. In the mining of sulphur one or more
wells extending to the sulphur containing de-
posit for introducing superheated water into
the deposit and removing the molten sulphur
110 therefrom, one or more wells extending to the
upper part of the deposit from which the sul-
phur has been exhausted, pumps so located
and designed to withdraw hot water at a tem-
perature above the melting point of sulphur
115 from the upper part of the deposit through
the last mentioned wells, means for maintain-
ing the withdrawn hot water under pressure
and returning it to said first mentioned wells,
means for withdrawing cold water at a tem-
perature below the melting point of sulphur
120 from a lower level of the deposit and one or
more wells provided with a supply of fresh
superheated water arranged to introduce the
same into the deposit and to remove molten
125 sulphur therefrom.

In testimony whereof I affix my signature.
ROBERT HOLDEN STEWART.
